DESIGN FOR A BOTTLE STOPPER OR THE LIKE

Arnold E. Aszody, Newark, N. J.

Application February 26, 1944, Serial No. 112,720

Term of patent 7 years

(Cl. D58—10)

To all whom it may concern:

Be it known that I, Arnold E. Aszody, a citizen of no country, last of Hungary, applied for citizenship in the United States, residing at Newark, in the county of Essex and State of New Jersey, have invented a new, original, and ornamental Design for a Bottle Stopper or the Like, of which the following is a specification, reference being had to the accompanying drawing, forming a part thereof.

In the drawing:

Fig. 1 is a front perspective view of a bottle stopper or the like, showing my new design.

Fig. 2 is a rear perspective view and

Fig. 3 is a bottom plan view of the same.

I claim:

The ornamental design for a bottle stopper or the like, as shown.

ARNOLD E. ASZODY.
